(57) **CLAIM**

The ornamental design for a surgical cannula guide, as shown and described.

DESCRIPTION

FIG. 1 is a front perspective view of a surgical cannula guide in accordance with the new design;

FIG. 2 is left side elevational view of the surgical cannula guide of FIG. 1;

FIG. 3 is a right side elevational view of the surgical cannula guide of FIG. 1;

FIG. 4 is a front elevational view of the surgical cannula guide of FIG. 1;

FIG. 5 is a rear elevational view of the surgical cannula guide of FIG. 1;

FIG. 6 is a bottom plan view of the surgical cannula guide of FIG. 1;

FIG. 7 is a top plan view of the surgical cannula guide of FIG. 1;

FIG. 8 is a front perspective view of a surgical cannula guide in accordance with a second embodiment of the new design;

FIG. 9 is left side elevational view of the surgical cannula guide of FIG. 8;

FIG. 10 is a right side elevational view of the surgical cannula guide of FIG. 8;

FIG. 11 is a front elevational view of the surgical cannula guide of FIG. 8;

FIG. 12 is a rear elevational view of the surgical cannula guide of FIG. 8;

FIG. 13 is a bottom plan view of the surgical cannula guide of FIG. 8;

FIG. 14 is a top plan view of the surgical cannula guide of FIG. 8;

(Continued)

FIG. 15 is a front perspective view of a surgical cannula guide in accordance with a third embodiment of the new design;

FIG. 16 is left side elevational view of the surgical cannula guide of FIG. 15;

FIG. 17 is a right side elevational view of the surgical cannula guide of FIG. 15;

FIG. 18 is a front elevational view of the surgical cannula guide of FIG. 15;

FIG. 19 is a rear elevational view of the surgical cannula guide of FIG. 15;

FIG. 20 is a bottom plan view of the surgical cannula guide of FIG. 15; and,

FIG. 21 is a top plan view of the surgical cannula guide of FIG. 15.
